Application filed December 15, 1894. Serial No. 531,982. Term of patent 3½ years.

To all whom it may concern:

Be it known that I, ARTHUR MIDDLETON ROSE, residing at Yonkers, county of Westchester, State of New York, have invented and produced a new and original Design for a Pattern to be Wrought into Wilton and other Carpetings in such coloring as may be designed; and I do hereby declare that the drawing accompanying this specification gives and conveys to any one skilled in the art of carpet weaving and manufacture a clear understanding of the same, and is sufficient to enable such person to use my invention.

The design consists of a body A and a border B.

The body A is decorated with flowers and buds of roses with sprays of foliage.

The border B is decorated with correspond-

What I claim as my invention, and desire to secure by Letters Patent, is—

1. In a design for a carpet, the body A, substantially as shown.
2. In a design for a carpet, the border B, substantially as shown.
3. The design for carpets, consisting of the body A, and the border B, substantially as shown.
